UNITED STATES PATENT OFFICE

144,460

DESIGN FOR A COMBINED HEEL AND PLATFORM FOR A SHOE OR SIMILAR ARTICLE

Jack Kowal, New York, N. Y.

Application June 14, 1945, Serial No. 120,102

Term of patent 3½ years

(Cl. D7—5)

To all whom it may concern:

Be it known that I, Jack Kowal, a citizen of the United States of America, residing in New York, county of New York, and State of New York, have invented a new, original, and ornamental Design for a Combined Heel and Platform for a Shoe or Similar Article, of which the following is a specification, reference being had to the accompanying drawing, forming part thereof.

Fig. 1 is a top perspective view of a combined heel and platform for a shoe or similar article showing my new design.

Fig. 2 is a bottom perspective view thereof.

I claim:

The ornamental design for a combined heel and platform for a shoe or similar article, substantially as shown.

JACK KOWAL.
